UNITED STATES PATENT OFFICE.

PEARL J. WENTWORTH, OF FORT THOMAS, KENTUCKY.

SHANK STIFFENER.

Application filed June 10, 1925. Serial No. 36,257.

My invention relates to shoes and is particularly directed to a shank stiffener for the same.

One object of my invention is to provide a shoe, the shank stiffener of which is securely attached to the heel to provide a spring board structure.

Another object of my invention is to provide a leaf spring shank stiffener for shoes. Another object of my invention is to provide a shank stiffener for a shoe, the flexibility of which will vary longitudinally.

Another object of my invention is to provide a shank stiffener for a shoe, one size of which shank stiffener can be used in shoes of different lengths.

Other objects and certain advantages will appear in the description of the drawings forming a part of this application in which drawings:

Figure 1 is a perspective view of my improved form of arch support.

Figure 2 is a side view of a shoe showing the arch support applied thereto, certain parts of the shoe being broken away to show the position of the arch support.

Figure 3 is a longitudinal sectional view of the arch support.

Figure 4 is a bottom view of a shoe showing the arch support positioned on the insole.

A shoe 1 is provided with an upper 2, insole 3, an outsole 4, a heel 5, and a sock lining 6. A shank stiffener 7 is placed between the insole and the outsole at the arch portion or shank of the shoe. This shank stiffener is of novel structure being made preferably from a single strip of flexible metal doubled back upon itself, forming a two layer structure for part of its length and a single layer structure for the rest of its length. The shank stiffener may be likewise described as a leaf spring. These two layers are held together in any convenient manner, such as by a tongue 9 bent from the metal of one layer extending through an aperture 10 of the other layer. The two layer end of the shank is adapted to

be securely attached to the heel of the shoe by means of a nail 11 driven through an elongated aperture 12 from the heel end of the shank stiffener, likewise through the insole, 50 outsole and into the heel. A forward or single layer portion of the shank extends just to the ground engaging portion of the shoe. The shank stiffener is bent to conform to the desired arch of the shoe and functions as a 55 spring board anchored to the heel, the spring board being more flexible at its forward end where the degree of arch is diminished. The firm mooring at the end of the heel prevents the rear end of the shank stiffener from tilting, and consequently tending to pry the insole and outsole apart. The shank stiffener is provided with an eyelet 8 through which passes a tack securing the stiffener to the insole to prevent it from pivoting on the heel 60 anchorage and becoming displaced. 65

The elongated aperture permits the same size shank stiffener to be used on various sized shoes, it being immaterial just how far back over the heel seat the shank stiffener extends. 70 For instance, one size shank stiffener can be used on shoes from $2\frac{1}{2}$ to $5\frac{1}{2}$ length and another size shank stiffener used on shoes varying between $5\frac{1}{2}$ and $9\frac{1}{2}$ in length. This obviates the necessity of a different size shank 75 stiffener for each different size shoe.

A shank stiffener of this structure is particularly adapted for ladies' high heel shoes.

Having described my invention I claim:

A shoe shank comprising a flat narrow strip 80 of metal bent upon itself, with one end extending beyond the other providing a pair of spring leaves of relatively different lengths, and a tang extending from one leaf clinched through an aperture in the other securing the 85 leaves together intermediate of their length, providing a rigid double layer rear portion and a flexible forward portion.

In witness whereof, I hereunto subscribe my name.

PEARL J. WENTWORTH.
